United States Patent Office

Des. 187,120

Patented Jan. 26, 1960

187,120

MOTOR OPERATED PENCIL SHARPENER

Robert G. Smith, Bronxville, N.Y., assignor to Minitone,
Inc., New York, N.Y., a corporation of New York

Application July 30, 1959, Serial No. 56,997

Term of patent 14 years

(Cl. D74—21)

FIG. 1

FIG. 2

FIG. 3

FIG. 4

FIG. 5

Figure 1 is a top perspective view of a motor operated pencil sharpener showing my new design.

Figure 2 is a front elevational view thereof.

Figure 3 is a side elevational view, the opposite side thereto being substantially identical in appearance.

Figure 4 is a rear elevational view.

Figure 5 is a top plan view thereof.

I claim:

The ornamental design for a motor operated pencil sharpener, as shown and described.
